FLEXIBLE HOSE

John Greczin, Philadelphia, Pa., assignor to Singer-Fidelity, Inc., Philadelphia, Pa., a corporation of Delaware

Filed Feb. 19, 1962, Ser. No. 68,887

Term of patent 14 years

(Cl. D43—1)

FIG. 2

FIG. 1.

FIG. 1 is a side elevation of a flexible hose showing my new design with a portion omitted to indicate indeterminate length and it being understood the repeatable knit pattern is continuous throughout.

FIG. 2 is an elevational view of an enlarged fragmentary section of the hose shown in FIG. 1.

The dominant features of my design reside in the portions shown in full lines.

The characteristic features of my design reside in the oppositely wound spiral strands forming a crisscross pattern.

I claim:

The ornamental design for a flexible hose, substantially as shown and described.
